UNITED STATES PATENT OFFICE.

CHARLES A. KINNEY, OF MERIDEN, CONNECTICUT, ASSIGNOR TO EDW.
MILLER & CO., OF SAME PLACE.

DESIGN FOR A LANTERN.

SPECIFICATION forming part of Design No. 13,008, dated June 27, 1882.
Application filed May 1, 1882. Term of patent 14 years.

To all whom it may concern:

Be it known that I, CHARLES A. KINNEY, of Meriden, in the county of New Haven and State of Connecticut, have invented a new 5 Design for Lanterns; and I do hereby declare the following, when taken in connection with accompanying drawings and the letters of reference marked thereon, to be a full, clear, and exact description of the same, and which said 10 drawings constitute part of this specification, and represent, in—

Figure 1, a perspective view; Fig. 2, a plan view.

This invention relates to a design for the 15 lower part or base of lanterns; and it consists in the shape of the base in transverse section, as shown in the accompanying illustration.

The central part, A, is cylindrical in shape. From each side outward projections B extend, 20 contracted or narrower than the central portion. The outer edge of these projections is

rounded and vertically in substantially semi-circular shape; but the shape of the outer edge is not material to this design. From the central part the base extends, forming an open 25 ring, C.

In the illustration I have shown my design as applied to a tubular lantern; but the part of the lantern above is immaterial, it only being essential that there shall be the usual appendages to complete the lantern.

I claim—

The herein-described design for the base of a lantern, consisting of the central cylindrical portion, A, with the contracted projections B 35 at each side, substantially as shown in the accompanying illustration.

CHAS. A. KINNEY.
